DETACHABLE BUTTON

Filed April 23, 1930

UNITED STATES PATENT OFFICE

ANDY CZOP, OF ALLENTEWON, PENNSYLVANIA

DETACHABLE BUTTON

Application filed April 23, 1930. Serial No. 446,581.

This invention relates to fasteners and has special reference to a button like fastener having parts readily applied to and removed from pieces of cloth, leather or the like which 5 are to be buttoned together to connect them and unbuttoned to permit their separation.

One important object of the invention is to provide an improved construction of such a fastener having the parts to be joined arranged 10 for screw connection.

A second important object of the invention wherein the button parts proper may be removed from the materials to be joined by simply unscrewing certain of the elements.

15 A third important object of the invention is the provision of a novel eyelet or grommet arrangement for protecting the cloth or other material around the fastener.

With the above and other objects in view, 20 the invention consists in general of certain novel details of construction and combinations of parts hereinafter more fully described, illustrated in the accompanying drawing and specifically claimed.

25 In the accompanying drawing, like characters of reference indicate like parts in the several views, and:—

Figure 1 is a dis-assembled face view of the two button parts in one form as applied 30 to the material to be connected;

Figure 2 is a face view showing the button with the two pieces of material in joined relation;

35 Figure 3 is a rear face view of one part of the button;

Figure 4 is a rear face view of the other part of the button;

Figure 5 is a section on the line 5—5 of 40 Figure 1;

Figure 6 is a section on the line 6—6 of Figure 1;

Figure 7 is a section on the line 7—7 of Figure 2;

45 Figure 8 is a view, similar to Figure 1, of a modified form of button;

Figure 9 is a view similar to Figure 2 of this modification;

50 Figure 10 is an inner face view of one part of the modified form;

Figure 11 is an inner face view of the other part of said modification;

Figure 12 is a section on the line 12—12 of Figure 8;

Figure 13 is a section on the line 13—13 of 55 Figure 8;

Figure 14 is a section on the line 14—14 of Figure 9.

The first form of the invention is shown as applied to two pieces of material 10 and 11. 60 The piece 10 is provided with a suitable opening surrounded by an eyelet or grommet which includes a ring 12 L-shaped in cross section and having one leg of the L pressed into the material adjacent said opening. 65 Passing through the opening is a tubular member 13 having a flange 14 which bears against the piece 10 on the side opposite the ring 12 and also having a flange 15 which laps the ring 12 so that the tube is securely 70 held in the material 10.

Journalled in the tube 13 is a tubular central or middle button part 16 provided at one end with a flange 17 which rests against the flange 14 and holds the part against pulling 75 through the grommet in one direction. The other end of this tube is externally threaded and carries a cap 18 which closes this end and holds the tubular middle part in the opposite direction. The threaded connection between the tube 16 and cap 18 is such that, with the cap screwed on as far as it will go, the tube 16 will turn freely in the grommet. 80

The piece 11 is also provided with a tubular button part 19 which is of proper size so 85 that one end can be threaded and screwed into the internally threaded end of the part 16. Plates 20 and 21, the latter having projecting prongs 22 engaging the material surround this member 19 on opposite sides of the piece 90 11. A keeper ring 23 is screwed onto the end of the member 19 at the end opposite the member 16 and thus holds the member 19 from drawing out of the material upon the two parts 16 and 19 being screwed together as 95 shown in Figure 7.

In the modified form of the invention shown in Figures 8 to 14 there is also disclosed two pieces of material 24 and 25. One 100 of these pieces carries a tubular button part

26 having a flared end 27 forming a head. A shoulder 28 formed under this head and rests on a plate or washer 29 which in turn rests on one face of the piece 24. Bearing 5 on the other face of this piece is a flange 30 formed integrally with the tube 26 and beyond this flange the tube is prolonged in a reduced and threaded end 31. The remaining member in this form has a tubular body 10 32 provided with an internally threaded portion to receive the threaded end 31. A washer plate 33 is provided on one face of the piece 25 and flanges 34 formed integrally 15 on the piece 32 bear against the washer plate and the other face of the piece 25 to hold this member of the button to the material.

In either case it is merely necessary to screw the two button members together to hold the two pieces of material together or 20 to unscrew said button members to permit separation of these pieces.

Having thus described the invention what is claimed is:—

A separable button consisting of two 25 separable members, one of which comprises a ring of L-shape in cross-section formed with a single inwardly directed flange, a tubular member of approximately U-shape in cross section, embracing the flange of said L-shaped 30 ring, said ring and tubular member being constructed and arranged to be inserted in a button hole and to engage with and compress the cloth between them, a second tubular member journaled in the aforesaid tubular 35 member and having an end flange abutting one end of the first named tubular member and a cap engaged with the other end of the second tubular member and abutting the first named tubular member to confine the two 40 tubular members in assembled relation.

In testimony whereof I affix my signature.
ANDY CZOP.
